SAFETY RAZOR

Application filed January 29, 1929. Serial No. 335,896.

The present invention relates to improvements in safety razors, and more particularly to a magazine razor of the type which employs blades in stacked relation and feeds them successively to shaving position, the blade fed to shaving position ejecting at the same time the used blade from the blade holder.

Razors of this type are old and well-known.

One serious difficulty experienced in the operation thereof consists in that the feeding mechanism of the device is apt to jam. The result is that, unless the user is fully acquainted with the construction of the device and is capable of disassembling and reassembling the elements thereof, the jammed razor must be returned to the factory for repairs. This is objectionable not only because of the trouble connected with such a procedure but also for the reason that the use of the razor is lost for some time.

The present invention relates to improvements in razors of the Schick type, one form of which is described in U. S. Patent #1,655,437, granted January 10, 1928. From an examination of the razor described in said patent it would appear that there are two general causes, incident to the construction thereof, which bring about jamming of the feeding mechanism. It will be readily understood that, when the feeding plunger of the said razor is moved to the end of its outward stroke, the topmost blade of the stack is caused to rise and is thereby brought into the path of the said plunger. When then the plunger is moved on its inward or feeding stroke, the said topmost blade is engaged by the plunger whereby the blade is fed through the discharge opening in the razor handle toward the blade holder. Ordinarily, no jamming takes place when the feeding stroke of the plunger is completed and the blade positioned on the holder. However, if, for some reason, the feeding stroke is not completed and the plunger is moved in the opposite direction as far as the construction will permit, the rear end portion of the blade below the topmost blade is caused to rise into the path of the plunger. When thereafter it is attempted to move the plunger again on its

feeding stroke, the blade below the topmost blade prevents such operation because it cannot be advanced toward the discharge opening in the razor handle, with the result that the feeding mechanism is jammed. The reason for this is that that end portion of the blade below the topmost blade, which is adjacent the discharge opening, is still located within the magazine, so that that end wall of the magazine which is located adjacent the discharge opening acts as a stop. It will be also noted from an examination of a razor of the Schick type that, when the feeding plunger is disposed wholly within the razor handle and it is moved from such position back and forth a short distance, it carries by friction the topmost blade of the stack toward the discharge opening. When the topmost blade is thus partly advanced and the feeding plunger is moved to the end of its feeding stroke, it jams because the discharge opening is of a size to permit ejection of a single blade only and cannot accommodate, at the same time, the ejecting finger on the feeding plunger. Therefore, when it is attempted to force the said finger into and through the discharge opening, when a blade is therein, the plunger will be jammed.

The main object of the present invention is to generally improve the construction of safety razors of the type mentioned with a view of overcoming the difficulties above referred to.

Another object of the invention is to embody in a razor of the type mentioned anti-jamming features so designed that they may be applied thereto, first, without changing the construction thereof; second, without unduly complicating the design; and, third, without materially increasing the cost of production of the same.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the sev-

eral parts and details of construction within the scope of the appended claims, without departing from the spirit or sacrificing any of the advantages of the invention.

Generally speaking, the invention consists of means for preventing the feeding plunger of the razor from completing an outward stroke unless it has previously completed a feeding stroke, thereby precluding the possibility of the rear end of a blade from rising into the path of the plunger before the topmost blade of the stack has been delivered into shaving position onto the blade holder, said means being in the case illustrated in the drawings in the form of a pawl on the magazine support, co-operating with a notch in the plunger. The invention consists of further means which prevents the topmost blade from being moved forward by friction between the same and the feeding finger of said plunger.

One of the many possible embodiments of the invention is illustrated in the accompanying drawings, in which:—

Figure 1 is a side elevation of a safety razor constructed in accordance with the present invention, the blade holder being shown in position in which a blade may be fed thereunto; Fig. 2 is a central vertical section taken through the handle and the elements located therein, the blade holder being shown in elevation; Fig. 3 is a top elevation of the magazine support, magazine and feeding plunger of the device, the plunger being shown at the beginning of its feeding stroke; Fig. 4 is a bottom plan view of the elements shown in Fig. 3, the plunger occupying the same position; Fig. 5 is a bottom plan view of the said elements with the plunger at the end of its feeding stroke; Fig. 6 is a similar view of a portion of the elements illustrated in Figs. 3 to 5, inclusive, showing the position of the pawl which it occupies on the feeding stroke of the plunger; Fig. 7 is a similar elevation showing the pawl in a position in which it prevents the plunger from completing its outward stroke; Fig. 8 is a section taken on line 8—8 of Fig. 5; Fig. 9 is a side elevation of the inner end portion of the feeding plunger; Fig. 10 is an elevation of the pawl of the device; Fig. 11 is a perspective view of the inner end portion of the magazine support; Fig. 12 is an enlarged sectional view of a portion of a blade holder, showing the razor handle, magazine support, magazine and feeding plunger in operative relations thereto; Fig. 13 is a sectional view similar to the one shown in Fig. 12, certain of the elements being in other positions; c. Fig. 14 is a side elevation of the magazine of the device; Fig. 15 is a top plan view thereof; and Fig. 16 is a section taken on line 16—16 of Fig. 14.

Referring now to the drawings, the numeral 20 indicates the handle of the razor,

the same being hollow and preferably quadrangular in transverse cross-section. To the upper end of the handle is fixed a standard 21 (Figs. 12 and 13), and on the latter is mounted, by means of a pivot pin 22, the 70 blade holder 23 of the razor. This holder is adapted to turn on the said pivot approximately 90 degrees from the position shown in Figs. 1 and 2 of the drawings. In the last-mentioned position, the holder is in alignment with the handle or, in other words, it forms a continuation thereof. The upper end of the handle is closed by the said standard, as clearly shown in Figs. 12 and 13 of the drawings, while its lower end is open, as 80 appears from Fig. 2 of the drawings, to permit of insertion thereinto of the feeding mechanism, the magazine support, the magazine and a spring co-operating with the latter, as will be more fully described herein- 85 after.

The blade holder does not form part of the present invention, and, therefore, a detailed description of the same seems to be unnecessary. It is sufficient to say that it is in the form of an oblong body having a blade supporting surface 24, with which co-operates a blade clamping member 25 for fixing the blade 26 in position upon the said blade supporting surface in proper relation to the guard 27. The blade is what is commonly known as a wafer blade, having a single cutting edge.

The bore 28 of the handle is quadrangular in transverse cross-section and has fitted into it a magazine support 29, which is in the form of a channel member, fixed in position within said handle. On this magazine support is slidably arranged a feeding plunger 30, which is also in the form of a channel member, the webs 31 and 32 of the magazine support and the feeding plunger, respectively, being opposed, that is to say the web 31 of the magazine support abuts against one of the side walls 33 of the handle and the web 100 32 of the plunger is in contact with the opposite side wall 34 of said handle, as clearly appears from Fig. 2 of the drawings. Means are provided, not shown, for limiting the outward movement of the plunger in relation 105 to the handle and said magazine support. To the outer end of the plunger is fitted a knob 35, in the form of a ring, to facilitate manipulating of the plunger and serving also as a stop for limiting the inward movement 110 thereof.

The blades are supplied to the purchaser ready for insertion into the magazine support, they being stacked in a magazine 36, which will be described in detail hereinafter. 125 This magazine is adapted to slide endwise and fit snug into the magazine support, it resting more particularly on inwardly extending longitudinal ledges 37 on the side flanges 38 and 38' of the magazine support, 130

the said ledges being disposed a suitable distance above the web 31 of said support.

With the magazine co-operates a spring 39, carried by a plug 40, which has an enlarged outer end 41, fitting the knob 35. For the purpose of fixing the plug and spring in proper relation to the stack of blades, the spring is provided with a projection 42 which is automatically seated in an aperture 43 in the magazine support when the plug is inserted into the handle after the magazine has been placed thereinto.

The magazine comprises a bottom 44, a front end wall 45, a rear end wall 46 and a side wall 47. Opposite the side wall 47 are formed along the end walls very short flanges 48, engaging the very corners of the cutting edges of the blades, so that the blades may be fed through without any injury to the cutting edge except possibly at the tip of each end. In the magazine bottom is formed an opening 44', through which the spring 39 projects, as clearly shown in Fig. 2 of the drawings. This spring bears against the stack of blades, so that they are constantly being pressed toward the side wall 34 of the handle, the topmost blade being brought into abutment with the inner face of the last-mentioned wall when the feeding plunger is moved on its outward stroke, as will clearly appear hereinafter. The side wall 47 of the magazine and the flange 48 on the front end wall 45 thereof are split, as indicated at 49, adjacent the bottom edge of said front end wall, thereby permitting the latter to be forced outwardly from the position shown in Fig. 12 of the drawings into that shown in Fig. 13, the said front end wall then swinging on its bottom edge on the magazine bottom. The said front end wall is provided with a projection 50 on its outer face, which is adapted to be seated in a recess 51 in the standard 21, said projection and recess serving to position the magazine on its support. As appears from Figs. 12 and 13 of the drawings, the recess 51 is larger than the transverse cross-section of the projection 50, for a purpose hereinafter to be described.

It will be noted from Figs. 11 to 13, inclusive, of the drawings that adjacent the inner end of the magazine support the ledges 37 thereon are each provided with two longitudinal incisions 52, and the material of the ledges between the said incisions is bent into the magazine support, constituting resilient supporting means on which the inner end of the magazine is adapted to rest. These resilient supporting means are so dimensioned that, when the feeding plunger is moved on its outward stroke and has passed a substantial distance beyond the front end wall 45 of the magazine (Fig. 12), the inner end of the magazine is moved by the said resilient supporting means toward the side wall 34 of the handle, the free transverse edge of the said

end wall being then positioned at a distance from the inner surface of the wall 34 which is less than the thickness of a razor blade. The recess 51, above referred to, is of a length to permit such movement of the inner end portion of the magazine. In order to permit the front end wall 45 of the magazine to swing from the position shown in Fig. 12 into the position shown in Fig. 13 of the drawings, the underface 53 on the standard 21 is inclined.

The web 32 of the plunger is provided at its inner end with a feeding finger 54, and in alignment with the latter is formed in the standard 21 a discharge opening 55 of a size to accommodate a single blade, the said discharge opening registering with the blade supporting surface 24 of the blade holder when the latter is in the position shown in Figs. 1 and 2 of the drawings, when it forms a continuation of the razor handle.

Adjacent the outer end of the magazine support extend through the flanges 38 and 38' thereof registering openings 56 and 57, respectively, the said openings being disposed below the ledges 37. Into these openings is fitted a pawl 58, shown in detail in Fig. 10 of the drawings, the said pawl extending transversely across the said magazine support and being wholly disposed below the said ledges so as not to interfere with the insertion of the magazine into the said support. This pawl is slidable in the openings 56 and 57 transversely across the magazine support and is mounted upon a blade spring 59, which is attached in any suitable manner at 59' to the magazine support on the outer face of its flange 38 below the ledge thereon. As appears clearly from Fig. 10 of the drawings, the pawl is provided adjacent its attachment to the spring 59 with a shoulder 60, and below the said shoulder with an inclined face 61. The free end of the pawl is hook-shaped, as shown at 62. With the inclined face 61 of the pawl is adapted to co-operate an inwardly extending inclined projection 63 on the adjacent flange 64 of the plunger, and with the hook-shaped end 62 of the said pawl is adapted to co-operate an inwardly extending inclined projection 65 on the opposite flange 66 of said plunger. The projection 63 is disposed near the knob end of the plunger and the projection 65 adjacent the inner end thereof. The projection 63 is so positioned that, on the feeding stroke of the plunger, it engages the inclined face 61 of the pawl immediately before the feeding stroke is completed, shifting the said pawl toward the flange 66 of the plunger and causing the hook-shaped end 62 to project through the opening 57 in the flange 38' of the magazine support and to engage the forward edge of the opening 57, whereby the pawl is locked in such position (Fig. 5). In this position

130

of the pawl, its shoulder 60 is spaced from the flange 64 of the plunger. The projection 65 is so positioned on said plunger that it engages the hook-shaped end 62 of the 5 pawl, when the latter is in its projected position shown in Fig. 5 of the drawings, immediately before the plunger completes its outward stroke, thereby unlocking the said hook-shaped end from the flange 38' of the 10 magazine support and permitting the spring 59 to swing the pawl so as to bring its shoulder 60 into engagement with the web 64 of the plunger. The elements are shown in these positions in Fig. 4 of the drawings.

15 In the free longitudinal edge of the flange 64 of the plunger is provided a notch 67 of a size to permit the shoulder and inclined edge of the pawl 58 to swing thereinto. This notch is located in rear of the feeding finger 20 54 a distance that its leading edge 68 is disposed in rear of the shoulder 60 of the pawl 58 when the feeding plunger has completed its outward stroke, as clearly shown in Fig. 4 of the drawings. This leading edge extends preferably at right angles to the free 25 longitudinal edge of the flange 64 of the plunger, as appears from Fig. 9 of the drawings. It is obvious that, when the elements are in the positions shown in Fig. 4 of the 30 drawings and the plunger is started on its feeding stroke, the shouldered edge of the pawl is projected by the spring 59 into the notch 67 when the said notch is brought into alignment with the pawl. In these positions 35 of the elements, the feeding finger projects over the rear end portions of the blades in the magazine. The purpose of this arrangement will be described hereinafter.

The operation of this device is as follows:

40 In order to charge the razor with a magazine containing a stack of blades, the plug 40, with its spring 39, is removed from the razor, and the charged magazine slid into the handle. After this the plug and the spring 45 are inserted, the latter passing through the opening 44' in the bottom of the magazine against the innermost of the stack of blades, as clearly shown in Fig. 2 of the drawings. The elements of the razor are then in the positions shown in Fig. 2 of the drawings, from 50 which it appears that the magazine bottom contacts throughout its length with the ledges 37 on the magazine support and the free transverse edge of the front end wall 45 of the said magazine is spaced from the wall 34 of the handle a distance corresponding to 55 the thickness of the feeding finger 54. The pawl 58 is then in the position shown in Fig. 5 of the drawings, in which it is locked by 60 the hook-shaped end 62 thereof engaging the forward edge of the opening 57 in the flange 38' of the magazine support (Figs. 5 and 8). As soon as the feeding finger is withdrawn 65 from the discharge opening 55 and has passed on its outward stroke beyond the front end wall 45, the resilient supporting elements of the magazine support shift the front end portion of the magazine toward the handle wall 34, the elements being then in the positions shown in Fig. 12 of the drawings, 70 from which it appears that the free transverse edge of the front end wall of the magazine is disposed from the inner face of the handle wall 34 a distance which is less than the thickness of a razor blade. Therefore, 75 when the plunger is moved back and forth through a short distance, it cannot move the topmost blade beyond the magazine, the friction between the feeding finger and the blade being not sufficient to force the front end wall 80 of the magazine into inclined position. Consequently, the last-mentioned wall forms a stop for the blade.

In order to feed a blade to shaving position and to eject the used blade, the plunger 85 is taken hold of by the knob 35 and pulled out of the handle as far as the construction permits. The feeding finger is then in a position in which it uncovers the mouth of the magazine, so that the topmost blade of the 90 stack is forced by the spring 39 against the inner face of the handle wall 34, whereby its rear transverse edge is adapted to be engaged by the said feeding finger. Disregarding now the action of the pawl and ratchet mechanism above referred to, it will be noted that, 95 when the plunger is moved on its feeding stroke, the topmost blade is advanced through the discharge opening in the razor handle onto the blade holder, the advancing blade at the same time ejecting the used blade from said holder. As soon as the advancing movement of the topmost blade starts, its front end portion forces the front 100 end wall of the magazine outwardly into the inclined position shown in Fig. 13 of the drawings, which gives sufficient clearance for the passage of the blade over the said front end wall. When the last-mentioned end wall is forced into inclined position, the front section of the magazine is lowered until the magazine bottom abuts throughout its length against the ledges 37, the resilient sections of the said ledges being caused to move into the plane of said ledges. 105 The front end wall of the magazine returns to its normal position and the magazine moves again toward the handle wall 34 as soon as, on the next outward stroke of the plunger, the feeding finger has passed some 110 distance beyond the front end wall of the magazine.

115 Considering now the action of the pawl mechanism, it will be noted that when the plunger has completed its outward stroke the pawl is in the position shown in Fig. 4 of the drawings, in which the hook-shaped end 62 thereof is unlocked from the flange 38' of the magazine support and the shouldered 120 opposite end of the said pawl bears against 125

130

the web 64 of the feeding plunger. When now the plunger is moved on its feeding stroke, the shouldered end of the pawl is projected by the spring 59 into the notch 67 in the plunger (Fig. 7), but is immediately unseated from the said notch by the rear edge of the notch 67 acting on the inclined edge 61 of the pawl. This inclined edge bears against the inner face of the flange 64 until it is brought into engagement with the projection 63, which is immediately before the completion of the feeding stroke of the plunger. As the feeding stroke is being completed, the pawl is moved into the position shown in Fig. 5 of the drawings, in which it is locked by the hook-shaped end 62 co-operating with the forward edge of the opening 57 in the flange 38' of the magazine support. In this position the shouldered edge 20 of the pawl cannot co-operate with the notch in the plunger. Immediately before the plunger completes its outward stroke, the plunger projection 65, co-operating with the hook-shaped end 62 of the pawl, unlocks the latter and thereby returns the elements into the position shown in Fig. 4 of the drawings. From the foregoing it appears therefore that although the pawl is locked and unlocked, that is to say rendered inoperative and operative at the end of the feeding stroke and outward stroke, respectively, of the plunger, the said pawl has no function during the normal operation of the device, that is to say while the said strokes are completed in either direction. However, when a feeding stroke has once been started, the plunger cannot be returned to a position in which it is capable of engaging the blade next below the topmost blade of the stack. As appears from Fig. 4 of the drawings, in which the plunger is shown at the beginning of its feeding stroke, the shouldered end of the pawl bears against the inner face of the plunger flange 64, it being in its unlocked operative position. When now the plunger is moved on its feeding stroke and it is thereafter attempted to return it to the starting point of its feeding stroke, the pawl spring 59 projects the shouldered edge of the pawl into the notch 67 as soon as the said notch is in alignment with the pawl. The pawl shoulder 60, in co-operation with the leading edge 68 of the notch, prevents further outward movement of the plunger, but obviously permits the plunger to move again on its feeding stroke. Inasmuch as the feeding finger projects over the rear end portion of the magazine when the pawl is seated in the notch 67, it is obvious that the rear edge of the blade below the topmost blade of the stack cannot rise into position to be engaged by the feeding finger and consequently the said blade cannot be advanced toward the discharge opening. The result is that jamming of the feeding mechanism cannot take place.

It is obvious that, while herein a specific pawl mechanism has been described for preventing the completion of the outward stroke of the plunger unless the previous feeding stroke has been completed, any other suitable means may be made use of without departing from the invention, which lies mainly in the provision of a mechanism which prevents engagement of a blade in the magazine by the feeding mechanism while another blade is still seated in the discharge opening of the device. It is also obvious that, while herein a specific mechanism has been described for automatically raising the forward end of the magazine to restrict the discharge opening after the feeding finger has been disengaged therefrom, any other means may be employed without departing from this feature of the invention, which lies mainly in the provision of a stop to prevent a blade from being advanced by friction toward the blade holder.

What I claim is:—

1. A razor including a handle provided with a discharge opening, a magazine within said handle adapted to hold a stack of blades, a plunger movable longitudinally on said handle for successively feeding blades from the stack toward said discharge opening, a spring-pressed pawl on said handle, said plunger being provided with a notch in which said pawl is adapted to be seated, said notch being positioned to prevent said plunger to complete its idle stroke when said pawl is operative, and means on said plunger for rendering said pawl inoperative immediately prior to the end of its feeding stroke and operative immediately prior to the end of its idle stroke.

2. A razor including a handle provided with a discharge opening, a magazine within said handle adapted to hold a stack of blades and having a yielding end wall adjacent said discharge opening, means for successively feeding blades from the stack toward said discharge opening, and means on said handle adapted to move that portion of said magazine which is provided with the yielding end wall toward said discharge opening when said plunger is being moved on its idle stroke and partly uncovers the mouth of said magazine, whereby said yielding end wall obstructs said discharge opening.

3. A razor including a handle provided with a discharge opening, a magazine support within said handle, a magazine on said support adapted to hold a stack of blades and having a yielding end wall adjacent said discharge opening, means for successively feeding blades from the stack toward said discharge opening, and means on said support adapted to move that portion of said magazine which is provided with the yielding end wall toward said discharge opening when said plunger is being moved on its idle stroke.

and partly uncovers the mouth of said magazine, whereby said yielding end wall obstructs said discharge opening.

4. A razor including a handle provided with a discharge opening, a magazine holder within said handle, a magazine mounted on said holder adapted to receive a stack of blades, a plunger movable longitudinally on said magazine holder for successively feeding blades from the stack toward said discharge opening, a spring-pressed pawl on said magazine holder, said plunger being provided with a notch in which said pawl is adapted to be seated, said notch being positioned to prevent said plunger from completing its idle stroke when said pawl is operative, and means on said plunger for rendering said pawl inoperative immediately prior to the end of its feeding stroke and operative immediately prior to the end of its idle stroke.

5. A razor including a handle provided with a discharge opening, a magazine holder within said handle, a magazine mounted on said holder adapted to receive a stack of blades, means for successively feeding blades from the stack toward said discharge opening, and co-acting means on said magazine holder and said feeding means for preventing the latter from engaging and advancing a blade from the stack toward said discharge opening before the topmost blade of the stack has fully passed through said opening.

6. A razor including a handle provided with a discharge opening, a magazine holder within said handle, a magazine mounted on said holder containing a stack of blades, a plunger movable longitudinally on said magazine holder for successively feeding blades from the stack toward said discharge opening, and co-acting means on said magazine holder and plunger permitting the latter to move freely on its feeding stroke but preventing the same from returning to the starting point of its feeding stroke unless it has previously completed a feeding stroke.

7. A razor including a handle provided with a discharge opening, a magazine holder within said handle, a magazine mounted on said holder containing a stack of blades, a plunger movable longitudinally on said magazine holder for successively feeding blades from the stack toward said discharge opening, and a pawl mechanism mounted on said magazine holder permitting said plunger to move freely on its feeding stroke but preventing the same from returning to the starting point of its feeding stroke unless it has previously completed a feeding stroke.

8. A razor including a handle provided with a discharge opening, a magazine holder within said handle, a magazine mounted on said handle containing a stack of blades, a plunger movable across the mouth of said magazine for feeding the topmost blade from the stack toward said discharge opening, and

co-acting means on said magazine holder and said plunger for preventing the latter from wholly uncovering the mouth of said magazine unless it has previously completed a feeding stroke.

9. A razor including a handle provided with a discharge opening, a magazine holder within said handle, a magazine mounted on said handle containing a stack of blades, a plunger movable across the mouth of said magazine for feeding the topmost blade from the stack toward said discharge opening, and a pawl mechanism co-operating with said plunger for preventing the latter from wholly uncovering the mouth of said magazine unless it has previously completed a feeding stroke.

10. A razor including a handle provided with a discharge opening, a magazine holder within said handle, a magazine mounted on said holder adapted to contain a stack of blades, a spring co-operating with said magazine for feeding the blades out from said magazine into position to be fed, a plunger movable longitudinally on said magazine holder having a finger for moving a blade from the stack toward said discharge opening, said spring acting when at the end of the idle stroke of said plunger said finger has wholly uncovered the mouth of said magazine, and co-acting means on said magazine holder and said plunger for preventing said finger from uncovering the mouth of said magazine unless said plunger has previously completed a feeding stroke.

11. A razor including a handle provided with a discharge opening, a magazine holder within said handle, a magazine mounted on said holder adapted to contain a stack of blades, a spring co-operating with said magazine for feeding the blades out from said magazine into position to be fed, a plunger movable longitudinally on said magazine holder having a finger for moving a blade from the stack toward said discharge opening, said spring acting when at the end of the idle stroke of said plunger said finger has wholly uncovered the mouth of said magazine, and a pawl mechanism on said magazine holder co-operating with said plunger for preventing said finger from uncovering the mouth of said magazine unless said plunger has previously completed a feeding stroke.

Signed at New York city, in the county of New York, and State of New York, this 28th day of January, A. D. 1929.

JOSEPH MUROS.
